COMBINED POWER-OPERATED CAN OPENER AND CLOCK

Sheldon M. Rutter, Miami, Fla., and Henry J. Talge,
Kansas City, Mo., assignors to John C. Hockery, Kan-
sas City, Mo., trustee

Application February 2, 1959, Serial No. 54,414

Term of patent 14 years

(Cl. D22—2)

Fig. 1 is a front elevational view of a combined power-operated can opener and clock embodying our new design.

Fig. 2 is a top plan view thereof;

Fig. 3 is a left side elevational view; and

Fig. 4 is a rear elevational view thereof shown in reduced scale.

We claim:

The ornamental design for a combined power-operated can opener and clock, as shown.
